SUPERHETERODYNE RECEIVER

William S. Barden, Grasmere, Staten Island,
N. Y., assignor to Radio Corporation of
America, a corporation of Delaware

Application April 1, 1933. Serial No. 663,905

9 Claims. (Cl. 250—20)

My present invention relates to superheterodyne receivers, and more particularly to a novel method of, and means for, suppressing undesired responses in radio receivers of the superheterodyne 5 type.

It is well known at the present time that a superheterodyne type of receiver may be embodied in a comparatively low priced chassis and cabinet. Such superheterodyne receivers, often 10 termed "midgets" or "sub-midgets", usually embody a first detector circuit, intermediate frequency amplifier, a second detector, an audio frequency amplifier, reproducer, and a certain amount of radio frequency amplification between 15 the antenna and the first detector circuit. However, because of the economy requirements in the construction of such low priced receivers, the degree of selectivity between the antenna and the first detector is not comparable to the relatively 20 higher degree of selectivity in a more expensive superheterodyne receiver.

One of the undesirable results of such insufficient radio frequency ahead of the first detector resides in annoying response due to heterodyning between undesired carriers. A particularly disagreeable type of undesired response in a superheterodyne receiver, where economy of construction is the prime consideration, occurs when two undesired carriers are impressed on the antenna circuit which differ by approximately the 30 intermediate frequency employed. The insufficient radio frequency selectivity ahead of the first detector permits these undesired signals to reach the first detector where they heterodyne, 35 and thereby cause an intermediate frequency component. The latter component in turn heterodynes with the desired intermediate frequency signal which has been produced by the 40 heterodyning of the local oscillation and the desired radio frequency carrier to which the radio frequency system is tuned.

Now, I have discovered a novel method of, and devised means for, suppressing undesired responses in a low priced superheterodyne receiver 45 wherein the undesired responses are caused particularly by undesired carriers differing by approximately the operating intermediate frequency, and which undesired carriers cannot be 50 blocked by sufficient radio frequency selectively ahead of the first detector.

Accordingly, it may be stated that it is one of the prime objects of the present invention to provide a superheterodyne receiver of the type 55 employing tuned radio frequency amplification

ahead of the first detector and intermediate frequency amplification between the first and second detectors, wherein the ratio of intermediate frequency gain to radio frequency gain is maximized to avoid undesired responses due to heterodyning produced by two undesired carriers differing by approximately the operating intermediate frequency.

Another important object of the present invention may be said to reside in the provision 65 of a superheterodyne receiver, of the type wherein economy of price and construction is the main consideration, the receiver being characterized by the fact that its intermediate frequency amplifier gain bears a predetermined relation to 70 its radio frequency amplifier gain, and this relation is such that undesired response caused by heterodyning of two undesired carriers differing by approximately the operating intermediate 75 frequency is substantially eliminated.

Another object of the present invention is to provide in a superheterodyne receiver, a device for simultaneously decreasing radio frequency amplification prior to the first detector and increasing intermediate frequency amplification 80 between the first and second detectors in a ratio such that there is substantially suppressed undesired responses due to the heterodyning of two undesired carriers differing by approximately the 85 operating intermediate frequency.

Other objects of the present invention are to improve generally the efficiency of low priced superheterodyne receivers, and to particularly provide a receiver of this type which is not only 90 economically constructed and marketed, but reliable in operation and free from undesired responses.

The novel features which I believe to be characteristic of my invention are set forth in particularity in the appended claims, the invention itself, however, as to both its organization and method of operation will best be understood by reference to the following description taken in connection with the drawings in which I have 95 indicated diagrammatically several circuit organizations whereby my invention may be carried into effect.

In the drawings,
Fig. 1 shows generally a superheterodyne receiver embodying the present invention,

Fig. 2 shows a graphical explanation of the present invention,

Fig. 3 shows a modified form of the invention,

Fig. 4 shows still another modification,

Fig. 5 shows still another modified form of the invention.

Referring now to the accompanying drawings wherein like reference characters designate similar circuit elements in the different figures, there is shown in Fig. 1 a superheterodyne receiver, which is to be understood as being of the so-called "midget" type, the receiver embodying the usual grounded antenna circuit A, a radio frequency amplifier having a tunable input, first detector having a tunable input, a tunable local oscillator, an intermediate frequency amplifier, and a second detector whose output is adapted to be coupled to an audio frequency amplifier and a reproducer. The tuning devices, such as variable tuning condensers, in the radio frequency amplifier, first detector and local oscillator circuits are arranged to be uni-controlled as shown by the dotted lines 1, in any well known manner. The tunable circuits of the radio frequency amplifier and first detector stages are tuned to a common signal frequency, and this differs from the local oscillator frequency by the desired operating intermediate frequency. The construction of a superheterodyne receiver of the type shown in Fig. 1 is too well known to those skilled in the art to require any further description.

In low priced superheterodyne receivers it is impossible to provide sufficient radio frequency selectivity ahead of the first detector because of cost considerations. It has been found that a particularly annoying type of undesired response occurs in such a low cost receiver when the antenna circuit picks up two undesired carriers which differ by approximately the operating intermediate frequency. The insufficient radio frequency selectivity ahead of the first detector permits these two undesired signals to reach the first detector. There they heterodyne and produce an intermediate frequency component which heterodynes with the desired intermediate frequency signal which has been produced by the heterodyning of the local oscillation and the desired radio frequency carrier to which the radio frequency amplifier and first detector are tuned.

Now, it can be shown that the undesired intermediate frequency component due to the two undesired carriers, say A and B, is proportional to the product of the intensities of A and B. If the gain of the radio frequency amplifier tube is halved, the strength of this undesired intermediate frequency component caused by A and B is quartered. The intermediate frequency amplifier gain is now doubled in order to maintain the original desired signal sensitivity. It will now be seen that the result of halving the radio frequency gain and doubling the intermediate frequency amplifier gain is to halve the strength of the undesired intermediate frequency component at the second detector.

Similarly, when the radio frequency amplifier gain is decreased four-fold, and the intermediate frequency amplifier is increased four-fold, the undesired intermediate frequency component, due to the product of A and B, is quartered. Therefore, as a fundamental principle in the design of a low cost superheterodyne receiver of the type shown in Fig. 1, there should be employed as low a radio frequency stage gain (grid of radio frequency tube to grid of first detector tube) and as high an intermediate frequency gain (over-all intermediate frequency system including conversion gain of first detector) as feasible, or practical, until limited by other considerations. This

has been found very desirable in the efficient operation, with minimum undesired response, of low cost superheterodyne receivers. In other words, it will be seen that the essential design principle involves the maximization of the quantity

$$\frac{\text{intermediate frequency gain}}{\text{radio frequency gain}}$$

In Fig. 2 there is shown charted, in a purely illustrative manner, the effect of the present invention in reducing the operating disadvantage already described. Under the title "Original Condition" there is shown in Fig. 2 the quantitative relation between the desired intermediate frequency component and the undesired intermediate frequency component whose effect is to be minimized. It will be noted that the desired intermediate frequency component is the product of the desired signal and the local oscillation, while the undesired intermediate frequency component is the product of the undesired carriers A and B. The ratio of desired intermediate frequency component to undesired intermediate frequency component is 8:1 in the example given in Fig. 2. Of course, the intensity units, and their graphic representation, are purely illustrative, and greatly exaggerated for convenient showing.

Under the title "Effect of Reduced R.F. AMPL." there is shown the quantitative relation between the desired intermediate frequency component and the undesired intermediate frequency component when the radio frequency amplification prior to the first detector is reduced in accordance with the present invention. It will be noted that the desired signal has been reduced to half of its original intensity, and the product, or desired intermediate frequency component is now 16 units. However, each of the undesired carriers A and B have been reduced to one unit in intensity, and their product is therefore one unit. Hence, it will be seen that the ratio between the desired and undesired intermediate frequency components is now 16:1.

Under the title "Effect of Increased I. F. AMPL." there is shown how the original signal sensitivity is restored by increasing the intermediate frequency amplification. The desired intermediate frequency component is now restored to its original 32 units, while the undesired component has been only increased to 2 units. Therefore, it will be seen that although the original signal sensitivity has been restored, the ratio of desired to undesired intermediate frequency component is still 16:1. In this way the present invention enables the undesired response due to the heterodyning of the undesired carriers A and B to be substantially suppressed, while the original signal sensitivity is substantially maintained. As has been pointed out heretofore the receiver shown in Fig. 1 may have its radio frequency amplifier and intermediate frequency amplifier originally designed to accomplish the effects graphically shown in Fig. 2.

In Fig. 3 there is shown a modification of the present invention wherein a superheterodyne receiver, of the type shown in Fig. 1, may include, in addition to the uni-control tuning mechanism 1, and the manual volume control (M. V. C.) 2, a device for suppressing undesired response of the type discussed above. This undesired response suppressor is schematically shown in Fig. 3 as comprising a variable resistance element 3 connected between the grid and cathode of the radio frequency amplifier tube 4, and a second

variable resistor device 5 connected between the grid and cathode of the intermediate frequency amplifier tube 6. A uni-control means 7, shown in dotted lines, may be connected in any desired 5 manner to mechanically couple the sliders 8, 9 of the devices 3 and 5 so that when the slider 8 moves in the direction of the arrow, to increase the negative bias of tube 4, the slider 9 moves in the opposite direction to decrease the negative 10 bias on the grid of tube 6.

In this way the effects graphically charted in Fig. 2 may be secured. In other words, the device 7 functions as a manual gain control for the radio frequency and intermediate frequency amplifiers, which gain control is independent of the manual volume control device 2 disposed between the output of the second detector and the input of the audio frequency amplifier. The number of sliders 8 and 9 may be so arranged that when the 15 gain of the radio frequency amplifier tube 4 is reduced by half then the gain of the tube 6 would be doubled. Of course, the device 7 would not be actuated by the operator of the receiver until the type of interference discussed above would 20 make itself manifest. The operation of this form of the invention is believed to be clear from the description of Fig. 2.

Fig. 4 shows a modification of the arrangement in Fig. 3 wherein a single grounded slider 30 10 is employed to cooperate with a single resistor 11 to vary the gain of the radio frequency and intermediate frequency amplifier tubes 4 and 6. Only such portions of the circuit are shown in Fig. 4 which are necessary to an understanding 35 of the invention. Thus, the first detector circuit is shown in Fig. 4 conventionally as a detector-oscillator stage, the construction of the latter being well known to those skilled in the art. In Fig. 3, this stage is generally designated as a 40 "frequency changer".

The variation in gain of the tubes 4 and 6 in Fig. 4 is produced by connecting the resistor 11 between the cathodes of tubes 4 and 6, and biasing the control grids of these tubes with respect to 45 the cathodes. Thus, when the tap 10 is moved along the resistor 11 towards the cathode of tube 6, then the negative bias of the grid of tube 4 with respect to its cathode is increased, while the negative bias of the grid of tube 6 is decreased.

50 The manual volume control in this figure is shown of a different type, and involves the use of a variable resistor 12 disposed in the screen grid circuit of tube 6. The operation of the arrangement shown in Fig. 4 is similar to that described in connection with Figs. 2 and 3.

In Fig. 5 there is shown still another possible 55 modification of the arrangement shown in Figs. 3 and 4. Here, the amplitude of the radio frequency energy impressed on the detector-oscillator stage is controlled by varying the radio frequency input to the radio frequency amplifier preceding the detector oscillator. This is accomplished by connecting the resistor 11 of Fig. 4 between the cathode of the intermediate frequency 60 amplifier tube 6 and the high potential side of the coupling M_1 . The grounded slider 10, when moved along resistor 11 simultaneously varies the amount of collected radio frequency signal shunted to ground and the negative bias of 65 the grid of the intermediate frequency amplifier tube 6.

Here, again, when the slider 10 is moved along 70 the resistor 11 towards the cathode of tube 6, the radio frequency signal input to the radio frequency 75 amplifier is reduced, while the intermediate frequency

frequency amplifier gain is increased. Hence, it will be seen that the operation of this modification of the invention results in the effects described in connection with Fig. 2. By reducing the amount of radio frequency signal energy collected by the antenna circuit to one half, for example, and simultaneously doubling the intermediate frequency amplifier gain, the ratio of desired intermediate frequency component to undesired intermediate frequency component will be doubled. Of course, 80 as stated in connection with Fig. 3, the slider 10 would not be adjusted until the type of undesired response referred to arises and is reproduced by the reproducer.

In the modification shown in Figs. 3, 4 and 5 it is to be clearly understood that adjustment of the undesired response suppressor may be made to cover a wide range of conditions. That is, the suppressor device could be adjusted to conform to the intensity of the undesired response. It is believed that the range of movement thereof will be obvious from the foregoing description, and it is to be clearly understood that this range of adjustment may be as wide as desired, or as small as desired, depending upon the undesired responses sought to be suppressed.

Moreover, while I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. A method of reducing undesired response in superheterodyne reception, which undesired response is produced by the heterodyning of at least two undesired carriers differing by substantially the operating intermediate frequency, which 115 consists in collecting the undesired carrier energy and the desired signal energy, reducing the amplification of the said collected energies substantially below a predetermined normal amplification level, impressing the amplified energies upon a 120 frequency changer whereby a desired intermediate frequency component derived from said desired signal energy is produced and an undesired intermediate frequency component derived from the product of said two carriers is 125 produced, and increasing the amplification of said desired and undesired components substantially above a normal amplification level, and maintaining the ratio of said amplification increase to said amplification reduction at a maximum.

2. A method of suppressing undesired response, in superheterodyne reception, caused by the heterodyning of two undesired carriers differing by substantially the operating intermediate frequency, which consists in simultaneously collecting desired signal energy and said undesired carrier energies, amplifying the said collected energies, impressing the amplified collected energies upon a frequency changer to produce a desired 140 intermediate frequency component which is derived from said desired signal frequency energy and an undesired intermediate frequency component which is the product of the said two undesired carrier energies, amplifying the desired 145 and undesired intermediate frequency components, and simultaneously reducing the said first amplification and increasing the said second amplification in a predetermined manner to substantially increase the ratio of said desired component 150

to said undesired component when the intensity of the latter becomes undesirable.

3. In combination, in a superheterodyne receiver, a first detector, a second detector, an intermediate frequency amplifier connected between the first and second detectors, and a radio frequency amplifier connected to the input of the first detector, the selectivity of the amplifier preceding said first detector being insufficient to prevent the production of undesired intermediate frequency component caused by at least two undesired carriers differing by substantially the operating intermediate frequency, and the gain of said radio frequency amplifier being of such a magnitude with respect to the gain of the intermediate frequency amplifier that the ratio of desired intermediate frequency component to the said undesired component is greatly increased.

4. In combination, in a superheterodyne receiver, a first detector, a second detector, an intermediate frequency amplifier connected between the first and second detectors, and a radio frequency amplifier connected to the input of the first detector, the selectivity of the amplifier preceding said first detector being insufficient to prevent the production of undesired intermediate frequency component caused by at least two undesired carriers differing by substantially the operating intermediate frequency, and means for adjusting the gain of said radio frequency amplifier to such a magnitude with respect to the gain of the intermediate frequency amplifier that the ratio of the desired intermediate frequency component to the said undesired component is greatly increased.

5. In combination, in a superheterodyne receiver, a first detector, a second detector, an intermediate frequency amplifier connected between the first and second detectors, and a radio frequency amplifier connected to the input of the first detector, the selectivity of the amplifier preceding said first detector being insufficient to prevent the production of an undesired intermediate frequency component caused by at least two undesired carriers differing by substantially the operating intermediate frequency, and means for decreasing the gain of said radio frequency amplifier to such a magnitude and increasing the gain of the intermediate frequency amplifier to such an extent that the ratio of the desired intermediate frequency component to the said undesired component is greatly increased.

6. In combination, in a superheterodyne receiver, a first detector, a second detector, an intermediate frequency amplifier connected between the first and second detectors, and a radio

frequency amplifier connected to the input of the first detector, the selectivity of the amplifier preceding said first detector being insufficient to prevent the production of an undesired intermediate frequency component caused by at least two undesired carriers differing by substantially the operating intermediate frequency, and a single means for decreasing the gain of said radio frequency amplifier to such a magnitude and increasing the gain of the intermediate frequency amplifier to such an extent that the ratio of the desired intermediate frequency component to the said undesired component is greatly increased.

7. In a superheterodyne receiver, a frequency changer, means for collecting signal energy of the broadcast frequency range, a selective circuit, including a frequency selection means, coupling said collecting means and said frequency changer, an intermediate frequency amplifier coupled to said frequency changer, the selectivity of said selective circuit being insufficient to prevent undesired carriers from reaching the frequency changer and producing a heterodyne frequency which is of a frequency substantially equal to the operating intermediate frequency, and means for simultaneously decreasing the intensity of the desired signal and undesired carrier energies impressed on said frequency changer to a predetermined fraction, and increasing the gain of said intermediate frequency amplifier by a number of times equal to the denominator of said fraction when the intensity of said undesired intermediate frequency component becomes undesirable.

8. In combination, in a superheterodyne receiver, a frequency changer circuit, a second detector circuit, an intermediate frequency amplifier coupling said frequency changer and second detector, a radio frequency transmission network coupled to the input of said frequency changer, and a single means for simultaneously decreasing the transmission efficiency of said radio frequency network and increasing the gain of said intermediate frequency amplifier in a predetermined manner with respect to said transmission efficiency reduction.

9. In a superheterodyne receiver, a first detector circuit, a second detector circuit, an intermediate frequency amplifier coupling the first and second detectors, a radio frequency amplifier connected to the input of said first detector, and means for simultaneously decreasing the gain of said radio frequency amplifier and increasing the gain of said intermediate frequency amplifier.

WILLIAM S. BARDEN.
